TERMINAL AIR BRAKE TIME TESTING DEVICE

Ernest E. Andrews, Richmond, Va.

Application June 11, 1956, Serial No. 590,473

3 Claims. (Cl. 73—39)

This invention relates to a testing apparatus. The invention is directed to testing the air brakes of railroad trains. More particularly, the invention relates to time controlled apparatus for testing railroad car brakes.

In general, the air brake system of railway car brakes includes an auxiliary reservoir for air under pressure, pneumatic plungers, triple valves, retaining valves and a brake pipe interconnected in a known way to operate brakes of a car. In use, the brake pipes of the several cars of the train are interconnected by means of flexible coupling hoses to provide a continuous air passage, known as the train pipe, extending from the locomotive to the last car of the train. In the locomotive, is the usual engineer's brake valve controlling a main reservoir of compressed air and, at the rear end of the train, the train pipe is closed.

This system is charged with air at normal brake operating pressures, that is about 60 pounds pressure. This normal operating pressure of 60 pounds retains the brakes of all the cars in the train in released position. Consequently, when the pressure in the train pipe is reduced, the brake apparatus on the cars operates to apply all of the brakes of the train, the brakes remaining in the applied position until the pressure in the train pipe is restored to its normal value. This control of the air pressure within the train pipe is effected in the usual manner through the engineer's brake valve or the emergency brake applying device located in each car, in the case of passenger trains.

When a train is made up at a terminal, and on some occasions, when the several cars are in the shop for repairs, it is necessary that the brakes of each car be tested and inspected. In making such a test, a testing apparatus is usually employed that is connected with a supply of compressed air and has valve means associated therewith to charge the train pipe with air under normal operating pressure. The testing apparatus usually includes gauges to determine the pressure within the train pipe and also to assist in determining whether or not the rate of leakage within the train pipe, if any, exists, is within permissive tolerances.

In the conventional manner of making tests by means of apparatus such as that above referred to, it is necessary that considerable time be consumed because of the fact that such apparatus is so arranged that it becomes necessary for the inspector to travel the length of the train four times in order to check whether the brakes are properly applied and properly released by the testing apparatus. Furthermore, such arrangements have the drawback of including special type fittings, expensive diaphragm valves, spring actuated pistons and spring actuated brake releasing valves, thereby adding to the cost of such testing apparatus and shortening the life thereof and increasing the maintenance since the complicated valve arrangements and the several spring devices require constant care and attention to maintain them in proper oper-

2

ating condition. Further, such prior known devices rely upon the pressure within the train system and the pressure applied by the testing apparatus to operate the brake releasing valve. Consequently, proper operation of this valve is dependent upon the condition of the various complicated and expensive valves existing in the testing apparatus and also upon the condition and rate of leakage in the train pipe itself. In one such known device, it is necessary for the inspector to bleed the train pipe line to effect the operation of the brake releasing valve of the testing apparatus.

The device of the present invention eliminates the drawbacks of these prior apparatus as it does not require any special valves or fittings, is not dependent upon the pressure in the system or the pressure applied to the system for effecting the operation of the brake releasing valve. Consequently, the testing apparatus built according to this invention is less expensive than known devices, requires practically no upkeep, since the parts, being of standard fittings, are readily replaceable, and the operating means for the brake releasing valve is entirely independent of the pressure in the train pipe on the testing system.

The present invention constitutes an improvement upon prior Patent 2,510,538.

Accordingly, an object of the present invention is to provide a relatively simple, inexpensive, light-weight, portable testing apparatus for testing the air brakes of railroad trains and having a new control for the brake release valve operating independently of the air pressure in the air brake system.

Another object of the present invention is to provide this new independently operating control of the air pressure in the air brake system by a new and more compactly designed time-control means.

A further object of the invention is to provide such a new, more compactly designed time-control means which is adapted to be more conveniently handled and more readily set up for use than the means disclosed in the prior patent above referred to.

Still another object of the invention is to provide a new time-mechanism operated control for the brake release valve which operates independently of the air pressure in the air brake system and which control for the release valve is free of the operating weight and cord means of the prior patent and, accordingly, makes possible the easier transportation, handling and setting up of the apparatus for use than is possible with the apparatus of the prior art, particularly the apparatus disclosed in the patent referred to.

The invention will be best understood from a consideration of the following detailed description taken in connection with the accompanying drawing forming a part of the specification, with the understanding that the invention is not confined to a strict conformity with the showing of the drawing but may be changed or modified in minor details within the scope of the appended claims.

In the drawings:

Fig. 1 is a view in side elevation of the apparatus of the present invention showing the air supply, the train pipe connection and a train of cars diagrammatically illustrated on a smaller scale;

Fig. 2 is an elevational view on an enlarged scale of the kick-off cam means associated with the timer mechanism for effecting the release of the control valve stem; and

Fig. 3 is a sectional view on an enlarged scale of the control valve showing the same held in open position against the resistance of spring means which constantly urges the valve plug to closed position.

Referring now more particularly to the drawings wherein like numerals in the drawing designate like parts in the several views, the brake testing apparatus as illustrated in Fig. 1 is constructed of standard pipes and pipe fittings and includes a coupling 10 for connection to a source of compressed air which is generally designated 12, through the medium of a flexible pipe or tube 14. The apparatus also includes a main supply line comprising a section of pipe 15 in which is connected a check valve 15. The end of the pipe line 15 remote from the coupling 10 is connected with one arm of a T-coupling 17, the opposite arm of which is connected with the pipe section 18. This pipe section 18 connects with one side of the manually controlled or operated rotary plug valve 19 which connects at its other side with one side of a T-coupling 20 by a short pipe section 21 while the opposite side of the T-coupling 20 is coupled by the pipe section 22 with one arm of the T-coupling 23.

The T-coupling 20 which is interposed between the manual valve 19 and the coupling 23 is connected to a pressure gauge 24 of the type conventionally used for testing or indicating air pressure. This gauge is arranged so that it will stand upright when the apparatus is suspended in position for use at the side of a car C which may be of the freight or any other type.

The opposite arm of the T-coupling 23 from that with which the pipe section 22 is connected has connected therewith the pipe section 25 with which is coupled the flexible air hose 26, the outer or remote end of which carries the conventional type of coupling 27 by means of which it may be connected to the air line of a train of cars. Such air line is indicated by the reference character 28 and, as hereinbefore stated, a train of cars is diagrammatically shown connected in the air line and each of which cars is designated 29.

It will be noted that the operating handle 19a for the manual valve 19 is so arranged that the inspector, when manipulating this valve, will face the gauge 24 so that he can easily watch the air pressure indication or fluctuations shown thereby.

The numeral 30 generally designates a bypassing or bridging air line across the valve 19 and gauge 24. This bypass conduit or line comprises a vertically disposed pipe section 31 which is connected at one end with the leg of the T-coupling 23 and which, at its other or upper end, is connected with the leg of a T-coupling 32. One horizontal arm of the T-coupling 32 has connected therewith the short pipe length 33 with the opposite end of which is connected the manually operated bleed valve 34 which is here illustrated as being of the rotary plug type and which, when opened, bleeds air to the atmosphere.

The bypass or bridging conduit 30 further includes the horizontal pipe 35 which is connected with the other side or horizontal leg of the T-coupling 32 while at its end remote from this coupling it is connected with the 90° angle coupling 36 which is directed downwardly and has connection with the downwardly extending pipe section 37.

The numeral 38 generally designates a self-closing valve which, as shown in Fig. 3, is of the reciprocating plug type. The side of this valve opposite the pipe 37 is connected by the short pipe 39 with the vertically directed leg of the T-coupling 17. Thus it will be seen that when the valve 38 is open, and the valve 19 is closed, air may flow across the bridging bypass to the far side of the air gauge 24 and re-enter the line with the ends of which the couplings 20 and 27 are connected, to flow from the compressed air source 12 to the train air line 28.

The self-closing valve 38 which is shown in detail in Fig. 3 comprises the body 40 through which extends the passage 41 with the opposite ends of which passage the pipes 37 and 39 are connected.

Extending transversely of the passage 41 is the plug 75

bore 42 in which is slidably positioned the reciprocable plug 43 which is of cylindrical form and has a transverse passage 44 therethrough which, when the plug is shifted in one direction, is brought into line with the two ends of the passage 41 to open the valve.

The plug at one end carries a stem 45 which passes through the conventional bonnet 46 to the exterior of the valve body and the opposite end of the bore 42 is closed by the nut 47 and between this nut and the valve plug 43 is an expansion spring 48 which constantly urges movement of the valve plug to valve closed position.

The body 40 of the self-closing valve is of the usual or conventional form in that it comprises perpendicularly related arm sections or parts and one of these parts or arm sections has the bonnet 46 connected therewith as shown and secured on such part inwardly of the bonnet is a collar 49 with which is integrally connected a rigid lever supporting arm 50, the outer end of which projects beyond the bonnet in the direction of the length thereof as shown. The outer end of the arm 50 has pivotally attached thereto by the pivot pin 51, an end of an actuating lever 52 which extends across the outer end of the stem 45 and the valve is mounted so that the lever or actuating arm 52 extends downwardly or toward the underlying pipe section 15 as shown in Fig. 1.

The lower end of the lever 52 is connected by a spring 53 with the adjacent parallel pipe section 39. This spring 53 is of sufficient strength that when it is free to pull on the lever 52, it will overcome the force of the spring 48 and thus the lever 52 will move the valve plug to the open position in which it is shown in Fig. 3.

Secured to the pipe section 15 on the side of the coupling 17 opposite from the valve 19, is a plate or platform 54. This platform may be secured to the pipe section 15 by U-bolts 55, as shown in Fig. 2, or may be welded to the pipe or secured in any suitable manner so that it will be maintained in horizontal position when the apparatus is mounted for use with the bypass conduit vertically disposed, as shown in Fig. 1. It is preferred that the platform project outwardly or upwardly from the car body on which the apparatus is suspended so that the timing apparatus which is generally designated 56 can be clearly seen by the inspector using the testing apparatus.

The timing apparatus or mechanism 56 is of the conventional type employed for timing the operation of various mechanisms such as X-ray machines or other pieces of equipment where it is desirable that some action be produced after the elapse of a selected time interval as, for example, the turning of a switch or the like. This timer mechanism 56 is set on the platform 54 so that the dial or face 57 will be directed outwardly and, as is well known, such timers are designed so that the hands in front of the dial or face may be set to indicate the time period which it is desired shall elapse before the timer operates to perform its desired function. The numeral 58 designates a kick-off or operating cam finger which is shown in Fig. 2 in a position which it assumes after release by the clock mechanism while the dotted line position of the cam is that to which the cam is turned for setting the clock or timer in operation.

Secured to the pipe section 15 between the timer mechanism 56 and the pipe 39, with which the control valve is connected, is a support or standard 59 on which is pivotally mounted at 60 a trigger lever 61. This lever 61 has a lower end which carries the trigger finger in the form of a bail or hook 62 which is directed upwardly and designed to engage one side of the lever 52 when the latter is pulled out against the resistance of the spring 53 to the position in which it is shown set in Fig. 1. This holds the lever 52 in the position where the spring 48 of the self-closing valve can function to move the valve plug to its closed position. When the trigger lever 61 is thus engaged with the valve control

lever 52, the upper end of the lever 61 can position across the kick-off cam after the latter has been turned down to the timer set position.

The numeral 63 designates a bracing strut or bar which is connected by the clamp brackets 64 and 65 between the upper end of the pipe section 37 and the pipe section 15 on the side of the timer mechanism remote from the control valve. The upper bracket 64 also has attached thereto a mounting or suspension hook 66 and a corresponding hook 67 is attached to the horizontal pipe 55 of the bypass conduit in horizontally spaced relation with the hook 66. These hooks provide means for suspending the entire testing apparatus on the side of the car C. This suspension of the apparatus is accomplished by engaging the hooks 66 and 67 over the conventional grab bar 68 which is secured to the side of the car body.

While the testing apparatus has been illustrated as mounted upon a grab bar secured to the side of the car body, obviously it may be supported upon any other suitable supporting means carried by the car body either on one side or the other or on the end thereof whichever location is the most convenient to the source of compressed air.

In addition, as will be readily obvious, the inlet end of the testing apparatus which constitutes the coupling 10 can be connected to the air compressor in an engine and the apparatus can be supported on the front of the car nearest to the engine.

In the operation of the apparatus constituting the present invention, the inspector connects the apparatus by the coupling 10 with the source of compressed air and then manipulates the inlet valve 19 to charge the train pipe line 28 to its required operating pressure for releasing the brakes. The valve 19 is then closed and the gauge 24 is checked in order to determine whether there is any leakage in the train pipe line. It will be understood, of course, that during this period the self-closing valve 38 will be in closed condition and the bleed valve 34 will also be closed. In the event that there is no leakage or if leakage exists, it is within permissible tolerances, the inspector then manipulates the bleed valve 34 to effect a suitable reduction of air pressure in the train pipe line, approximately 20 pounds, in order to effect the application of the brakes of the cars. The bleed valve 34 is then closed and an inspection is made of the brakes to make sure that all of the brakes are in proper working order and are in set position. During the foregoing checking operation, the timing apparatus has been set and is operating, it being understood, of course, that during such operation, it will be holding the automatic valve 38 in closed position as shown in Fig. 1. In other words, the time period which the clock mechanism is set to operate is sufficient to permit the checking and to cover the time required for the inspector to walk the length of the train while examining the brakes in their set position. This time interval is, of course, controlled by the length of the particular train being inspected. When the prescribed time interval has elapsed, the kick-off cam 58 of the timing mechanism is released and rotates to its upright position in which it is shown in Fig. 2 and, in so rotating, it rises against the underside of the trigger lever 61 and oscillates the lever so as to lower the latch finger 62 which disengages the valve lever 52 as shown in dotted outline in Fig. 2. This permits the automatic valve 38 to be opened by the action of the control spring 53 which pulls the lever 52 inwardly toward the body of the valve and shifts the plug 43 to the open position shown in Fig. 3 against the resistance of the spring 48. The air under pressure then flows through the bypass conduit 30 around or across the closed manual valve 19 and the gauge 24 and into the car-connected end of the apparatus, flowing through the coupling 27 into the car pipe line 28, and raising the

pressure in the pipe line 28 to effect the release of all of the brakes in the cars of the train. The inspector then merely returns along the length of the train examining the brakes to be sure that they are in their released position and, upon reaching the starting point, it is only necessary for him to disconnect the testing apparatus and render his report.

With this apparatus, where especially long trains are being tested, time may be saved by two inspectors each walking half the length of the train after the preliminary manipulation of the apparatus has been completed so that after the time control has functioned to recharge the pipe line of the train and release the brakes, each of the inspectors will have only half the train length to travel for making the final inspection.

The embodiment of the invention shown in the accompanying drawing is merely illustrative of the main feature thereof, which is the improved time-control mechanism and the manner of associating it with the self-closing valve for effecting the recharging of the train pipes to place the brakes in their released position.

I claim:

1. An air brake testing apparatus comprising an air line for effecting a connection between a source of compressed air and a train pipe of a line of coupled cars whose brakes are to be tested, means for controlling the supply of air to initially charge the train pipe to its normal pressure, means for reducing the pressure in the train pipe to apply the brakes, a compressed air bypass supply leading around the first means for facilitating recharging the train pipe to release the brakes, a self-closing control valve in said bypass, said valve comprising a reciprocable plug and stem connected with the plug and spring means urging movement of the plug to valve closed position, spring actuated means acting against said stem in opposition to and with greater force than the first spring means to move the plug to valve open position, latch means for holding the spring actuated means from overcoming the force of the first spring means to maintain the valve closed, and a time controlled means for releasing the latch means to effect opening of the valve by the spring actuated means.

2. The invention according to claim 1, wherein the spring actuated means comprises a pivotally mounted lever extending across and engaging the outer end of said stem, the lever when swung in one direction forcing the stem and plug to move to valve open position against the action of the first spring means and a spring connected with the lever to force it to move in said one direction and said latch means being adapted to engage said lever, and said time controlled means including a kick-off cam for applying lever releasing thrust to the latch means.

3. An air brake testing apparatus comprising an air line for effecting a connection between a source of compressed air and a train pipe of a line of coupled cars whose brakes are to be tested, means for controlling the supply of air to initially charge the train pipe to its normal pressure, means for reducing the pressure in the train pipe to apply the brakes, a compressed air bypass supply leading around the first means for facilitating recharging the train pipe to release the brakes, a self-closing control valve in said bypass, said valve including a reciprocable plug and a stem connected to the plug and a spring urging movement of the plug to valve closed position, a support secured to the air line adjacent to the valve stem, a time controlled mechanism mounted on said support and including a quick action kick-off cam movable from a set position to a kick-off position upon expiration of a predetermined time lapse, a pivoted latch lever mounted adjacent to said mechanism and having one end positionable to be struck by the kick-off cam in its movement between said positions, a pivoted lever engageable with said valve stem and when moved in one direction forcing the stem to valve open position,

means for releasably coupling the latch lever with the stem engaging lever when the said one end of the latch lever is in position to be struck by the cam for holding the stem engaging lever in valve closed position, and spring means for forcing the stem engaging lever in said one direction when disengaged from the latch lever.
